[57] CLAIM

The ornamental design for a chair, as shown and described.

DESCRIPTION

FIG. 1 is a front perspective view of a chair showing my design;

FIG. 2 is a rear three-quarter perspective view of my design;

FIG. 3 is a view in front elevation;

FIG. 4 is a view in side elevation, said view being a from the left aspect of FIG. 2;

FIG. 5 is a view in rear elevation;

FIG. 6 is a plan view;

FIG. 7 is a front three-quarter perspective view of a second embodiment of my design, which is essentially the same as that shown in FIGS. 1-6, with the exception that it is not provided with arms; and

FIG. 8 is a three-quarter perspective view of the embodiment shown in FIG. 7.
